SHOE STRETCHER

Application filed October 28, 1930. Serial No. 491,726.

It is one object of the invention to provide a stretcher that will permit the application of pressure to the sides and upper portion of the toe and adjoining parts simultaneously, or to the side portions alone, as occasion may require.

It is another object of the invention to provide a stretcher of the character indicated whereby means is provided for holding the laterally expanding elements true to their normal plane of movement, and means for automatically and positively sealing the said elements in their normal position when not extended.

It is also an object to provide means for preventing twisting of the expanding toe elements.

It is still another object of the invention to provide a stretcher of the character indicated that may be readily adjusted to stretch a shoe at the point or points desired, that will be economical to manufacture, strong and durable, positive in operation, and highly efficient in its practical application.

In the drawings:

Figure 1 is a plan view of a stretcher embodying our invention.

Figure 2 is a perspective view of the same with parts removed.

Figure 3 is a side elevation of the central toe stretching means with the operating shoe in place.

Figure 4 is a rear elevation of the same.

Figure 5 is an inside elevation of one of the laterally expanding stretcher elements.

Figure 6 is a plan view of the operating shoe.

Figure 7 is a side elevation of the same.

In the embodiment of the invention as herein disclosed we show at 1 a base member as designed for use in a woman's shoe and having the following characteristics. The portions 2 and 3 are disposed in angular relation to each other, the bottom portion 2 having a flat upper surface and having similar angular recesses formed in its sides as shown at 4 and 4a. A slot 5 is formed in portion 2 crosswise therethrough.

The upstanding angular portion 3 has a recess 6 formed in its face, the central por-

tion of the bottom 7 of the recess being parallel with the face, and the sides of the recess having shoulders 8-8 formed thereon and sloping forwardly as shown to provide cam surfaces for the shoe hereinafter described. An opening 9 is formed in bottom 7 to permit access to the shoe when in place. The upper end of portion 3 has a forwardly extending shoulder 10 formed thereon and is formed as at 11 to form a part of the bearing for the operating handle, and as at 12 to receive the collar hereinafter referred to.

A resilient plate 13 is mounted on the end of portion 3 as indicated at 14, this plate carrying the expansible members now to be described.

At 15 is shown a top piece adapted to seat on shoulder 10, the formations at 16 and 17 being complementary to the formations 11 and 12 in part 3. This piece is mounted upon plate 13 at its end as shown at 18. In the under side of piece 15 is formed a recess 19, and in the forward end of its upper surface are formed arcuate sockets as 20 and 20a. Fingers 21-21a are identical in form and mounting. Finger 21 is shown with a flange 22 seated in socket 20, and with its outer side lying in the plane of the outer side of base member 1 as at 23. Its bottom surface 24 rests upon base 1 in part, the part 25 being flush with the bottom of piece 15 and lying parallel with the face of portion 3 of base 1 but spaced therefrom by shoulder 10 to form guideway 26. The finger 21 is held in place, by means of a leaf spring 27 seated in a groove 28 in piece 15 and the said finger, and secured by screws. A short leaf spring 29 reinforces the upper end of spring 27, and the springs snugly fitted in the groove 28 in order to prevent the finger twisting relative to the piece 15. The fingers 21-21a have cam grooves as 30-30a formed in their parts 25-25a in complementary relation to each other and as a continuation of recess 19. A groove 31-31a is also formed crosswise of fingers 21-21a and in their lower surfaces 24-24a.

At 32-32a are shown the two expansible side elements having their outer surfaces shaped to the general conformation of the

shoe, and each element having a cam surface at 33—33a formed in its inner surface as shown. These elements are mounted upon plate 13 at their ends as shown at 34—34a, and are normally held seated in recesses 4—4a in base 1 and flat against the sides of base 1 and fingers 21—21a by means of a spring 35 connected thereto and passing through groove 31—31a in fingers 21—21a. These side elements are also provided with guides as 36—36a which engage the slot 5 in base 1 and thereby prevent the elements from moving in any direction other than in the plane of the base.

15 The spreading of these several resiliently mounted elements is effected by means of a shoe 37 having a top rib 38 adapted to slide in recess 19 and cam groove 30—30a, laterally extending arms 39—39a adapted to pass through guideways 26—26a and engage cam surfaces 33—33a, and a heel 40 adapted to engage the bottom 7 of part 3 or the cam surfaces 8—8 as desired. The heel 40 has a square hole 41 formed in the top thereof to engage a square peg 42 on shoe 37 and is secured in place by a screw 43. A spring 44 is placed in the heel to bear against the shoe so that when the screw is loosened the heel may be slipped off of the peg and turned at right angles to its first position and again secured in position without having to pull it away from the shoe. The heel is oblong in shape whereby to slide between the cam surfaces when in one position and to ride upon them when in the other position.

The operating rod 45 is connected to the shoe as shown at 46 and engages a threaded nut 47 in recess 17—12.

When the device is assembled as described 40 the several resiliently mounted members are spread by advancing the shoe 37 and returned to their normal positions by retracting the same. In advancing the shoe with the heel 40 in the position shown in Figures 3 and 4 45 the elements 32—32a are spread against the tension of spring 35 by the arms 39—39a operating against the cam surfaces 33—33a, the engaging guides 36—36a and slot 5 preventing the same from working upwardly. In 50 this movement the heel 40 engages the cam grooves 30—30a and spreads the fingers 21—21a laterally. When the shoe is fully retracted the heel 40 may be turned into the position shown in Figures 6 and 7 by operating through opening 9, then when the shoe is advanced the parts 21—21a and 32—32a are spread laterally and at the same time the heel rides up on cam shoulders 8 and spreads the central assembly 15—21—21a upwardly.

60 It is to be understood, of course, that while we have herein shown and described but one specific embodiment of the invention, changes in form, construction, and method of assembly and operation may be made 65 within the scope of the appended claims.

We claim:

1. A shoe stretcher comprising a base, resilient means mounted thereon, a pair of opposed spreader elements connected to the resilient means and normally paralleling the sides of the base, a spreader element mounted on top of the base and connected to said resilient means, means for spreading the elements against the tension of the said resilient means, and means inserted between the base and the elements for holding the opposed elements against displacement relative to their normal plane of movement.

2. A shoe stretcher comprising a base, resilient means mounted on one end thereof, a pair of opposed spreader elements connected to the resilient means and normally paralleling the sides of the base, a spreader element mounted on top of the base and connected to said resilient means, means for spreading the elements against the tension of said resilient means, means for holding the opposed elements against displacement relative to their normal plane of movement, and resilient means connecting the opposed spreader elements and adapted to urge the same into engagement with the sides of the base.

3. A shoe stretcher comprising, a base, resilient means mounted on one end thereof, said base having a guideway formed therein crosswise thereof and adjacent its other end, a pair of opposed spreader elements connected to the resilient means and normally paralleling the sides of the base and having arms thereon adapted to slidably engage said guideway, a spreader element mounted on top of the base and connected to said resilient means, and means for spreading the elements against the tension of said resilient means.

4. In a stretcher of the character described, a top spreader element having shoulders formed in one end of its upper surface, said shoulders having arcuate inner edges oppositely disposed with relation to each other, a pair of oppositely disposed fingers abutting the top element and having shoulders formed thereon to seat in the shoulders in said top element, and spring means mounted on the sides of the top element to engage the outer sides of the fingers to urge them toward each other, the said top member having a groove formed in its under side, and said fingers having cam grooves formed in their opposing sides in continuation of the groove in the top.

5. In a stretcher of the character described, a spreader shoe having an upstanding rib thereon and provided with oppositely disposed laterally directed arms, and an oblong heel member adjustably mounted on the side opposite said rib.

6. In a stretcher of the character described, a spreader shoe having an oblong

heel member adjustably mounted on one side thereof, releasable means for securing the member in position, and resilient means adapted to urge the member away from the shoe when released.

5 7. A shoe stretcher comprising, a base having a centrally disposed groove formed longitudinally therein adjacent one end and having cam surfaces formed on either side of the groove, resilient means mounted on said end of the base, spreader elements mounted on the resilient means to seat against the base, and a shoe mounted on the base to engage the several spreader elements and having a part adjustable to ride in the groove or on the cam surfaces to actuate selected spreader elements.

10 8. A shoe stretcher comprising, a base member, resilient means mounted on one end thereof, a pair of opposed spreader elements connected to the resilient means and normally paralleling the sides of the base, a spreader element mounted on top of the base and connected to said resilient means, means 15 for spreading the elements against the tension of said resilient means, and resilient means connecting the opposed spreader elements at a point remote from the first resilient means and adapted to urge the same into engagement with the sides of the base.
